PLUG TYPE PIPE CLOSURE

Joseph W. Gallop, East St. Louis, Ill., assignor to
Key Company, East St. Louis, Ill., a corporation
of Missouri

Application June 5, 1943, Serial No. 489,793

3 Claims. (Cl. 138—95)

My invention relates to a plug type pipe closure such as that employed in connection with refinery fittings or similar devices which are subjected to great variations in temperature and pressure during use in order to provide a reliable closure which may be readily removed to give access to the tubes to which such fittings are applied.

The present invention is specifically directed to variations in the details of construction of the form of closure shown and described in my co-pending application Serial No. 487,847, filed May 21, 1943. Like the form of closure shown therein, the present form employs, for seating the plug, inclined planes located on enclosed parts of the device rather than upon the casing itself. Thus my invention obviates the use of screw threads for seating the plug and consequently the employment of critical metal capable of being threaded, as well as the use of taps and chasers for the formation of such threads. Further, the inclined planes for seating the plug are so located that they are easily machined. This would not be the case if one of the planes, or coordinate sets of planes, were formed on the casing which, particularly in refinery fittings, is difficult to machine because of its size and shape.

In the accompanying drawings, which show one form of my invention embodied in a terminal fitting, Figure 1 is a vertical section; Figure 2 is a similar section taken at right angles to Figure 1; Figure 3 is a top plan view; Figure 4 is a view similar to Figure 2 but showing the casing only; Figure 5 is a cross section taken on the line 5—5 of Figure 2; Figure 6 is a side elevation of the plug; Figures 7, 8 and 9 are bottom, top and side views, respectively, of the equalizing member; Figures 10 and 11 are bottom and side views, respectively, of the holding member; and Figure 12 is a section taken on the line 12—12 of Figure 4.

The device consists essentially of four parts, a body or casing provided with a vent, a plug positioned in said vent, a holding member, and an equalizing member located between the holding member and the plug. In the drawings the casing 1 is a terminal fitting provided with a tapered vent 2 to give access to the tube (not shown) to which the fitting is applied by any suitable means, such as rolling the tube into serrations 3 on the fitting. The casing is provided with a flanged outlet 4. Formed on the interior of the upper end of the casing are a pair of oppositely disposed holding lugs 5. Each of these lugs preferably extends through an arc of about 90° and have their under bearing faces 6 machined flat. Surrounding vent 2 is a recess or counterbore 7

forming a gauge line for machining the faces 6 which must be located accurately. Formed in opposite sides of the casing about flush with the upper end of the vent are two openings 8, preferably rectangular in form. Positioned on the inner surface of the casing adjacent the openings 8 are four locating lugs disposed in two opposing pairs 9 and 10, respectively. Thus these two pairs of lugs provide two opposed pairs of recesses, 5 one of which serves to locate the plug and the other the equalizing member, as will be described later. It will be noted that the lengths of the lugs 9 and 10 are such that the included angle A of one set of recesses is somewhat greater than 10 the included angle A' of the other set. I have found this arrangement desirable in properly locating the parts.

Seated in the tapered vent opening 2 is a tapered plug 11. On the upper face of the plug 20 is a reduced portion 12 at opposite sides of which are lugs 13 projecting beyond the main part of the plug. These lugs cooperate with the ends of lugs 9 and 10 to position the plug and to also form overhanging lips to assist in releasing the 25 plug from its seat by means of a pry bar or similar tool inserted through openings 8 in the wall of the casing. The upper face of the reduced part 12 of the plug has a central recessed or relieved portion 14 to provide an annular bearing 30 face 15. This face is finished to form a convex spherical zone having its center C in the axis of the plug (Figure 2). The relieved portion 14 is provided with a threaded central opening 16 for the reception of a plug remover.

35 The holding member 17 is cylindrical in form and on opposite sides is provided with lugs 18 adapted to pass down between lugs 5 on the casing, and the top faces of said lugs 18 are machined flat to cooperate with flat faces 6 of lugs 5. 40 Projecting downwardly from the under sides of lugs 18 are a pair of oppositely slanted inclined planes 19 for cooperation with a similar pair of planes on the equalizing member. On the upper face of member 17 is a hexagonal head 20 for engagement with a wrench. The holding member 45 is also provided with a central opening 21 for the passage of a stud on the equalizing member.

The equalizing member has a disk-shaped body 22 on which are oppositely disposed projections 23. These projections, like lugs 18 on the holding member, pass down between lugs 5 on the casing. The upper faces of these projections 23 form a pair of oppositely slanted inclined planes 24 for cooperation with inclined planes 19 on the holding member. Extending 55

downwardly from the lower faces of projections 23 are a pair of lugs 25 for cooperation with lugs 9 and 10 on the casing. The lower face of this member has a concave spherical depression 26 curved on the same radius as zone 15 tapered plug 11 and cooperating therewith. Projecting upwardly from member 22 is a central stud 27 passing through opening 21 in holding member 17 and threaded to engage with nut 28.

To assemble the device, plug 11 is seated in vent 2 with its lugs 13 between lugs 9 and 10 and facing openings 8. The equalizing member is now dropped into position and given about a one-quarter turn in a clockwise direction. This will allow its lugs 25 to drop between lugs 9 and 10 until the lower concave face 26 contacts the convex zone 15 of the plug. The clockwise movement should be continued until the forward ends of lugs 25 bear firmly against the adjacent edges of lugs 10, thus insuring the proper angular position of the equalizing member. The holding member 17 is now dropped into position and given about one-quarter of a turn in a clockwise direction. This causes the plug to be forced into its seat due to the wedging action of the inclined planes 19 and 24. To secure sufficient pressure on the plug a wrench is applied to the hexagonal head 20 of the holding member. The cooperating spherical faces 15 and 26 permit sufficient rocking movement of the equalizing member to compensate for any slight defects in the construction of the device and thus insures uniform pressure throughout the circumference of the plug. After the plug has been properly seated lock nut 28 is applied to the stem to prevent accidental backing off the holding member through jar or any other cause.

Having fully described my invention, what I claim as new and desire to secure by Letters Patent of the United States is:

1. In a device of the class described, the combination with a casing having a vent opening and a plurality of inwardly projecting bearing lugs, of a plug member for said opening, said plug member having a convex bearing face, a holding member having lugs engageable with the lugs on the casing by rotary movement, an equalizing member located between the plug member and the holding member, said equalizing member having locating means engaging with the casing and a concave bearing face cooperating with the convex face of plug member, cooperating inclined planes acting between the equalizing and holding members to apply seating pressure to the plug member by relative rotary movement be-

tween said holding and equalizing members, and locking means between said latter named members to prevent accidental release of the seating pressure on the plug member.

2. In a device of the class described, the combination with a casing having a passage therethrough open at both ends, locking lugs on the casing adjacent one end opening, means for securing a pipe in the opposite end opening, a vent in the casing positioned between the openings and giving access to the latter named one, a plug for the vent, a holding member engaging with the lugs on the casing by rotary movement to secure said member in the casing, cam means comprising cooperating inclined planes each extending through less than a complete circumference, one of which planes is carried on the under part of the holding member, an equalizing member located between the holding member and the plug, said equalizing member carrying the second cooperating plane and having rocking engagement with the plug for imparting seating pressure to the latter through rotary movement of the holding member; and a locking stud carried by the equalizing member and engaging with the holding member to prevent accidental release of the seating pressure on the plug.

3. In a device of the class described, the combination with a casing having a passage therethrough open at both ends, locking lugs on the casing adjacent one end opening, means for securing a pipe in the opposite end opening, a vent in the casing positioned between the openings and giving access to the latter named one, a plug for the vent, a holding member engaging with the lugs on the casing by rotary movement to secure said member in the casing, cam means comprising cooperating inclined planes each extending through less than a complete circumference, one of which planes is carried on the under part of the holding member, an equalizing member located between the holding member and the plug, said equalizing member carrying the second cooperating plane and having rocking engagement with the plug for imparting seating pressure to the latter through rotary movement of the holding member, a pair of lugs on opposite sides of the plug, a second pair of lugs on opposite sides of the equalizing member; and two pairs of recesses in the casing wall angularly disposed with respect to each other for engaging with the lugs on the plug and equalizing member to locate said parts in proper position in the casing.

JOS. W. GALLOP.
